Primary Examiner — Jack Reickel*Assistant Examiner* — Bobby W Jones, II(74) *Attorney, Agent, or Firm* — Womble Bond Dickinson (US) LLP(57) **CLAIM**

The ornamental design for a hand shower, as shown and described.

DESCRIPTION

FIG. 1 is a front isometric view of a hand shower according to our new design;

FIG. 2 is a rear isometric view thereof;

FIG. 3 is a right side view thereof;

FIG. 4 is a left side view thereof;

FIG. 5 is a front view thereof; and,

FIG. 6 is a top view thereof.
